Manufacturing Company, Canton, Ohio, a cor-
poration of Ohio, and one-half to Shoup Voting
Machine Corporation, Union City, N. J., a cor-
poration of New Jersey

Application December 29, 1934, Serial No. 759,730

3 Claims. (Cl. 164—99)

This invention relates to voting machines and more specifically to an improved supporting structure for the marking device incorporated within the primary voting unit of the machine.

5 The improvement embodying the present invention is illustrated as coordinated with a machine of the character disclosed in an application by Samuel R. Shoup et al., filed July 25, 1929, Serial No. 380,839, although the device is adapted for use upon machines of other types.

10 The object of this invention is to provide marking wheel supporting structure and guideway therefor which is efficient of operation, sturdy of construction and economic of manufacture.

15 Referring to the drawing in which a preferred embodiment of this invention is illustrated—

Figure 1 is a fragmentary view of the interior 20 of the voting machine illustrating in plan view one of the marking wheel devices, the supporting structure and guideway therefor.

Figure 2 is a side elevational view of the apparatus illustrated in Figure 1.

25 Figure 3 is a detail view in perspective illustrating the marking wheel, the supporting frame therefor and the guideways embodied in said frame.

Figure 4 is a detail view in perspective illustrating the manner in which the pull straps are 30 mounted and the manner in which the marking wheels are guided in the voting machine frame.

35 Referring to Figures 1 and 2 the voting machine cabinet 10 embodies a panel 11 having apertures therein which are provided with sliding cover plates 12 disposed in vertical columns in the forward face of the machine. Rearward the cover plates 12 there is a platen 13 over which there is trained a paper sheet 14 prefer- 40 ably drawn from a roll 15 and gathered upon a drum 16. The drum is arranged for ready removal so that the votes indicated by the inscription upon the paper may be expeditiously tallied when the polls are closed. In a general 45 election the votes cast by the inscription method may be tallied independent of any political party affiliation. In primary election, however, it is essential that the party identification of the candidate be known. It is, therefore, customary 50 at such elections to require the voters to declare their party choice to an election officer who thereupon adjusts the machine so that no candidate under a party other than that declared may be voted, or for the voter to adjust the

mechanism to limit the voting operation to that of a single political party.

5 In the voting machine in which the present invention is embodied a party lockout mechanism is provided which, as heretofore described, is controllable by an officer authorized to restrict the operation of the machine to the candidates grouped under the declared political party. The mechanism constituting the party lockout device is fully disclosed in application Serial No. 380,839 10 aforesaid and since the present invention only contemplates structural improvements in such mechanism a further description thereof, other than reference to the actuating straps thereon, is deemed unnecessary in the present applica- 15 tion.

When a voter in a primary election wishes to vote for an individual whose name does not appear on the election ballot he retracts one of the plates 12 released for actuation by the 20 election officer and inscribes, or otherwise suitably marks, the name of the individual of his personal choice upon the paper 14. Upon operation of the voting mechanism the name thus voted will be identified with the political party 25 of his declared affiliation. Such identification is effected by operation of the voting mechanism and consequent actuation of one of a group of marker wheels or rolls 17 adapted to perforate or stamp the paper with suitable indicia, or to 30 identify the political party by the position of such marking relative to the arrangement of the parties in the primary lockout device.

35 The marking rollers 17 embodied in the present invention are mounted upon a plate 18 hav- 35 ing a flanged marginal edge 19, a portion of which is looped to form a yoke 20 for supporting a pin 21 upon which the roller 17 is mounted. The hub portions of the marking rollers are of such diameter that upon actuation they will 40 abut the platen 13, thus forming a stop and permitting only the pin points of the wheels to perforate the paper ballot. On the outer face of the flange 19 and adjacent the plate 11 of the voting machine cabinet there is a pull strap 22 45 which extends transversely across the face of the machine in guideways or notches 23 formed in the flanged portion of a frame 24 secured upon the inner face of the panel 11. Adjacent the outer wall 25 of the voting machine cabinet there 50 is a channel iron 26 having slots 27 machined in the forward flange thereof which is of suitable width to accommodate the reentrant engagement of the plate 18. The channel 26 is disposed slightly forward the panel 11 to permit 55

reciprocal movement of the flange 19 and the superimposed pull strap 22 intermediate the forwardly disposed flange thereof and the panel 11. Horizontally aligned with the slot 27 there is a slot 28 machined in the inturned legs 28a of the channel 26. The slot 28 constitutes a guideway for the lower face of the plate 18, the slots in the flange of the channel being of adequate length to provide suitable clearance for the reciprocal translation of the roller 17. To accommodate machining variations in the parts and variations due to assembly, the legs 28a of the channel 26 may be bent upward or downward to insure alignment of the marking rollers 17 within the machined slots 13a in the platen 13. In the accompanying drawing three sets of marking rollers are illustrated but it is to be understood that one of these rollers is employed for each political party in the ballot and that the machine is constructed to accommodate variation thereof.

In operation, when the voter declares his party affiliation and causes the proper pull strap 22 to be actuated the marking roller 17 will be advanced to perforate or otherwise mark the paper 14. Thereafter should the voter inscribe a name upon the paper a record is formed which coordinates the vote with the voter's party choice. The marking rollers 17 are disposed subjacent the cover plates 12 for each political party, which prevents the perforations from mutilating the paper upon which a person has written the name of his personal choice. The pull strap 22 when actuated is guided in the slots 23 in the frame 24, the plate 18 being supported and guided in the slots 27 and 28. In this construction the alignment of the rollers are suitably maintained yet the frictional losses are negligible since the guideway bearing surfaces are confined to the narrow edges of the channel stock upon which the plate 18 is supported. The roller support embodied herein possesses the further advantage that it may be readily assembled within the machine and that it is susceptible of removal without displacement of the roller plate 18 in the event repair or adjustment is necessary to mechanisms appurtenant the marking device.

Although the foregoing description is neces-

sarily of a detailed character, in order that the invention may be completely set forth, it is to be understood that the specific terminology is not intended to be restrictive or confining, and that various rearrangements of parts and modifications of structural detail may be resorted to without departing from the scope or spirit of the invention as herein claimed. 5

We claim:

1. A marking mechanism support comprising 10 a plate, a vertically disposed flange on one edge thereof, an extended portion therein folded downward parallel the base of said plate forming a yoke for holding a marker wheel, a channel having slots therein defining guideways, said 15 plate being disposed in said guideways and having a portion of said vertical flange disposed adjacent an outer edge of one leg of said channel to form a lateral guide, the yoke portion of said plate being disposed remote the portion of the 20 plate engaged by said guideway to facilitate reciprocal movement of the plate within the guideway.

2. A marking mechanism support comprising 25 a plate, a vertically disposed flange on one edge thereof, means for supporting a marker on said plate, a channel having slots therein defining guideways, said plate being engaged in said guideways, a second plate disposed adjacent and parallel a leg of said channel, the vertical flange 30 of said first named plate being disposed intermediate said second named plate and said leg of said channel thereby forming a lateral guide for said first named plate.

3. A marking mechanism support comprising 35 a plate, a vertically disposed flange on one edge thereof, means for supporting a marker on said plate, a channel having slots therein defining guideways, said plate being engaged within said guideways, a member parallel one leg of said 40 channel and spaced therefrom, the vertical flange of said plate being disposed intermediate said member and said leg of said channel, the portion of said plate engaged within said guideways being disposed relative the marker to permit 45 reciprocal movement of said plate.
